UNITED STATES PATENT OFFICE.

DAVID ROTHSCHILD, OF CINCINNATI, OHIO.

DESIGN FOR A SALOON FIXTURE.

SPECIFICATION forming part of Design No. 22,222, dated February 14, 1893.

Application filed December 27, 1892. Serial No. 456,485. Term of patent 3½ years.

To all whom it may concern:

Be it known that I, DAVID ROTHSCHILD, a citizen of the United States, and a resident of Cincinnati, in the county of Hamilton and State of Ohio, have invented a certain new and useful Design for Saloon Fixtures, of which the following is a specification.

My invention is a new and original design for a saloon fixture consisting of counter and wall fixture, the leading features of which are the back or wall fixture proper with its forwardly projecting cornice, the counter and its ornamentation, and the columns resting upon the end pedestals of the counter and supporting the forward ends of the cornice, as shown in the accompanying drawings, in which

Figure 1 is a front elevation of one half of fixture with a portion of the counter and the front of the cornice broken away to expose the parts back of them. Fig. 2 is an end elevation of the same and Fig. 3 is a similar view of the upper portion of the end with the outer framing of the cornice broken away to expose the arch or canopy portion within the outer frame.

In order to render the description of my new design clear, I will first describe in detail the wall fixture proper below the arched canopy or cornice. I will then describe the counter and then the cornice or canopy portion projecting from the wall over the counter and in connection therewith, will also describe the supporting columns which rest upon the counter and support the forward end of the cornice.

The lower or side board portion A of the wall fixture, aside from its forward ornamentation, is not different from the closet portions of fixtures used for this purpose generally. It has, however, the upwardly projecting portion A' covered by a top a, straight from end to end. The portion A' is fitted with doors having bevel edged panels, as shown in the broken away portion of Fig. 1, and the forward edge of frontly projecting part A' is corbeled by a beaded molding. The forwardly projecting portion of the side board is apparently supported by pilasters A² with carved capitals a' and the overlying projecting portion A' is broken above the pilasters by forwardly projecting blocks which have carved sunk panels. The back portion

which rests upon the top a has a rectangular carved molding or frame inclosing a reflecting panel or glass B in the center portion. 55 Upon each side of this back center portion is an arched molded frame inclosing a bevel edged reflecting mirror B'. Upon each side of the arch are carved spandrels. Resting upon the top a, upon each side of the arched 60 panel B', are columns C. These columns are surmounted by carved capitals which project above an ovolو molding b. The columns C are what might be termed anti columns or caps, that is, they are not completely round 65 but are cut away so as to rest against the back fixture, and the molding b is broken by the interposition of the upper or finial portion of the capital. These capitals c do not support any portion of the cornice but terminate 70 in an ornamental finial c'. The molding b forms practically the upper finish of the back or wall portion of the fixture above the side board portion and below the cornice or canopy portion. 75

The counter, the top of which is in practically the same horizontal plane as the top A' of the closet portion of the wall fixture, consists of the end pedestals D, the base d, the top plinth d', the top d² and the intervening 80 space between the base d and plinth d', which is broken by a recessed portion d³ and the pilasters d⁴. The panel portion between the base d, plinth d' and the pilasters d⁴, is fitted with reflecting bevel edged glass panels d⁵ 85 and d⁶, the panels d⁶ being circular and the panels d⁵ having their upper and lower edges in straight parallel planes and their ends concentric to the circular panels d⁶. The panels d⁶ are surrounded by carved foliage upon 90 their end adjacent to the pilasters, while the spaces between the circular panels and the concave ends of the panels d⁶, are ornamented with turned knobs or buttons. The front of the counter is further enriched by end and 95 intermediate panel pilasters d⁷, which have carved foliage upon the portions opposite the panel portion of the counter, and the upper portions of these pilasters which are divided from the lower portion by carved molding d⁸, 100 are enriched by carved ornaments, above the carved molding d⁸ and between the plain molding which corbels the top of the counter. The canopy or cornice portion E rests at

- its rear, upon the top molding *b* of the back of the wall fixture. The rear portion springs up in the form of the spandrels *e*. Upon these spandrels *e*, looking from the end, the cornice 5 *E* apparently rests. It consists of the upper or cap molding *e'*, below which is a continuous row of dentals *e''*, and curtain, or what might properly be called a frieze *e'''*, which is corbeled by an enriched ovolو molding *e^1*.
- 10 The parts above described form the outer finish of the cornice or canopy, with the addition of the returned corners which apparently break over the frieze portion, the corners being enriched by a mask or animal head.
- 15 *C'*, conventionally treated. The forwardly projecting end of the canopy is supported by rectangular finial columns *F*, the front and sides of which are recessed and enriched with foliage twining around reflecting nodules *f*,
- 20 the columns *F* resting upon pedestals *D* at the end of the canopy and bearing underneath the conventionally treated head *C'* of the cornice. The columns *F* have an enriched molded capital, above which is carved foliage
- 25 or scroll work forming the abacus and connecting with the heads or masks *C'*.
- The back portion of the fixture at each end and between the end columns *C*, curves around to meet the outer edge of the end panel *G*.
- 30 This portion of the fixture is fitted with bevel edged reflecting plates near the end portion of the bevel edged oval reflecting door plate *g*, which has above and below it similar reflecting surfaces forming spandrels.
- 35 Springing from the back fixture and extending the entire length of the wall fixture
- is an enriched frame work *H* (see Fig. 3 and the broken away portion of Fig. 1). This frame work is fitted with bevel edged reflecting panels, as clearly shown in Fig. 1, the object being to reflect the light, especially if electric lights are used to illuminate the fixture, down upon the counter and the articles which might be contained upon the side board portion. 40
- 45 The effect of the design is heightened by the illuminating, reflecting surfaces, especially when the fixture is illuminated by incandescent electric lights. When such are used, the effect will be greatly enhanced by 50 making the shafts of the columns *C* and pilasters *A^2* of some highly polished material of a different shade from the wood work or the fixture; such, for instance, as marble, onyx or other material having a reflecting surface. 55
- The particular counter shown and described, while of my invention, is not separately claimed herein, as it is obvious that its ornamentation may be varied without varying the general effect of the fixture, the features of 60 which are the wall fixture, the canopy and the columns which rest upon the counter and support the forwardly projecting portion of the canopy.
- 55 What I claim is—
- A design for a saloon fixture substantially as herein shown and described.

DAVID ROTHSCHILD.
